UNITED STATES PATENT OFFICE.

HELMUTH J. GAESS, OF PALISADE, NEW JERSEY, ASSIGNOR TO VESCO BAIT CO., OF NEW YORK, N. Y.

ARTIFICIAL BAIT.

Application filed March 21, 1922. Serial No. 545,410.

To all whom it may concern:

Be it known that I, HELMUTH J. GAESS, a citizen of the United States, residing at Palisade, in the county of Bergen and State 5 of New Jersey, have invented a certain new and useful Improvement in Artificial Baits, of which the following is a specification.

The invention relates to artificial baits used in fishing, and more particularly to the 10 eyes carried thereby to which the line-swivels, fish-hooks, and like equipments are attached.

The object of the invention is to provide an eye of simple and light construction 15 adapted to be permanently and rigidly fastened to the bait, and formed to permit the ring of a fish-hook or swivel to be readily engaged therewith or disengaged therefrom, and which will hold such engaged ring 20 strongly and reliably against the strains of service and accidental disengagement.

The invention consists in certain novel features and details of construction and arrangement by which the above objects are 25 attained, to be hereinafter described and claimed.

The accompanying drawings form a part of this specification and show several preferred forms of the invention.

30 Figure 1 is side view of a bait equipped with two of the improved eyes with a fish-hook and swivel engaged therein.

Figure 2 is a transverse section through such bait, taken on the line 2—2 in Figure 1, 35 and showing one of the eyes and its engaged fish-hook in edge view.

Figures 3 and 4 are face views of the two portions forming together the eye shown in Figures 1 and 2.

40 Figure 5 is an edge view of a modified form in which the two portions are integral and brought into proper relation by folding at the midlength.

Figure 6 is a face view showing the same 45 structure before folding.

Figure 7 is a face view showing another modification formed by bending a single piece of wire.

Figure 8 is a corresponding edge view.

50 Referring to Figures 1, 2, 3 and 4, the eye is composed of two plates of metal or other strong resilient material, adapted to

be applied on opposite faces of the bait 10 and strongly joined to the latter and to each other by rivets 11 extending through both 55 plates. The free ends of the plates project downwardly beyond the edge of the bait, side by side and slightly separated.

The plates are marked 12 and 13 and the projecting ends terminate in hooks 14 and 60 15, the curved bights of which are parallel and coincident with each other, with the points projecting oppositely in the same direction so that the entrance-opening of each hook is covered by the overlapping shank 65 of the other thus forming a closed eye, as clearly shown in Figure 1.

Both hooks may be of the same length but it is preferable that one, as 14, be slightly longer than the other, 15, as a further 70 safeguard against the unintentional release of an engaged ring.

The ring 16 of the swivel 17 is engaged by forcing it between the hooks, which spring outwardly enough to admit it, and passing 75 it over the point of the shorter hook 15, it is then moved along the shank of the shorter hook until it reaches the point of the longer hook 14 and is passed over the latter. Thus engaged the swivel is loosely held in 80 the eye formed by the overlapped hooks and may swing freely therein while held reliably against escape. The ring 18 of the fish-hook 19, or other like ring or loop, is similarly engaged and held in the other eye. 85 A reversal of the operation releases the ring.

In Figure 5 the hooks 21 and 22 are formed on the opposite ends of a single plate 20, as shown in Figure 6, which is folded closely upon itself through a portion of its length, leaving the hooks slightly separated for the insertion of a ring as above described.

Figures 7 and 8 show a further modification in which the hooks 24 and 25 and the body portion 23 are all formed of a single piece of wire bent at each end to form the oppositely disposed hooks, and the folded body portion is flattened in the plane of 95 the hooks and perforated to receive rivets. 100

Other modifications may be made in the forms and proportions especially in respect of the body or base portions and the manner

of attaching the latter to various types of baits. The essential feature is the oppositely disposed hooks forming the eye.

I claim:—

- 5 1. In an artificial bait, an eye formed by two oppositely disposed hooks arranged side by side, the point of one of said hooks being longer than that of the other, and means for attaching said hooks to such bait.
- 10 2. In an artificial bait, two plates adapted to be fastened to opposite faces of a bait and to each other with their free ends projecting beyond the edge of such bait, a hook on each of said free ends, said hooks ar-

ranged side by side in parallel planes and 15 separated from each other, with the points of said hooks oppositely disposed to form an eye.

3. In an artificial bait, the eye described comprising a body portion adapted to be 20 fastened to such bait, and two oppositely disposed separated hooks on said body portion, arranged in parallel planes and side by side, the point of one of said hooks being of greater length than that of the other. 25

In testimony that I claim the invention above set forth I affix my signature.

HELMUTH J. GAESS.
